LOCK CAP

Filed June 26, 1931

Frederick Greene

BY *Victor J. Evans*
and Co. ATTORNEY

UNITED STATES PATENT OFFICE

FREDERICK GREENE, OF NEW EAGLE, PENNSYLVANIA

LOCK CAP

Application filed June 26, 1931. Serial No. 547,089.

This invention relates to lock caps or closures for various types of containers and has for the primary object, the provision of a device of the above stated character which will efficiently seal a container against leakage and the unauthorized removal of the contents thereof but will permit the container to be easily and quickly filled or emptied thereby providing a device especially adaptable for all types of containers and especially desirable for hot and cold water bottles to be used in treating sick people and prevent them from obtaining the ice or water from the bottles, and also may be employed on fuel tanks of motor vehicles and the like to prevent theft of the fuel.

Another object of this invention is the provision of a lock cap or closure of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 7 is a top plan view illustrating a lock cap or closure applied to a fragmentary portion of a container constructed in accordance with my invention.

Figure 2 is a side elevation illustrating the same.

Figure 3 is a sectional view taken on the line 3—3 of Figure 1.

Figure 4 is a sectional view taken on the line 4—4 of Figure 3.

Figure 5 is a detail view illustrating one of the securing hooks.

Referring in detail to the drawing, the numeral 1 indicates an annular plate having formed thereon a marginal upstanding flange 2. The plate 1 is positioned over the neck 3 of the container 4 with a portion of the neck bent over the plate as clearly shown in Figure 3. A threaded sleeve 5 is positioned in the neck 3 and has formed thereon an annular

flange 6 overlying the portion of the neck disposed over the plate 1 and fasteners in the form of screw-threaded bolts 7 pass through the flange 6, the portion of the neck disposed over the plate and through the latter for establishing a leakproof connection between the plate and the container 4.

Pairs of slots 8 are formed in the plate 1 within the marginal flange 2 and one slot of each pair is adapted to have extended therethrough hook-shaped securing elements 9 formed on the periphery of a cap or closure member 10, the edges of which extend within the marginal flange 2. The fastening elements 9 after passing through the respective slots have the bill portions 11 thereof disposed in the adjacent slots of said pairs of slots to prevent direct separation of the cap from the plate but on a slight relative movement of the cap relative to the plate the bill portions 11 may be moved out of their respective slots so that the securing elements 9 may be drawn through or replaced in their respective slots.

An inner closure member 12 of substantially cup shape fits within the sleeve 5 in spaced relation thereto and has formed thereon a marginal flange 13 overlying the flange 6 and a suitable gasket 14 is interposed between the flanges 13 and 6. The inner wall of the cup shaped inner closure has formed thereon a seat 15 in which is journaled the head 16 of a screw-threaded stem 17 and the latter has threaded engagement with the internally screw-threaded boss 18 formed on the cap or closure 10. The bore of the boss 18 aligns with an opening formed in the cap or closure 10 to permit the shank of a key 19 to be inserted therein for engagement with a shank 20 formed on the stem 17 whereby the latter may be rotated for the purpose of moving the cap or closure 10 toward and from the plate 1 and when the cap 10 with the fastener elements 9 is properly positioned within the slots 8 and moved away from the plate a tight seal will be established between the flange 6, gasket 14 and flange 13 of the sleeve 5 thereby preventing the contents from leaking out of the container. The container may be constructed from any

material suitable for the purpose and when the device is employed upon fuel tanks of motor vehicles, the flange 13 adjacent the cup shaped portion will be provided with vent openings.

5 From the foregoing description taken in connection with the accompanying drawing, it will be noted that the device may be easily and quickly applied to a container and may be removed therefrom should it be desired to replace the container by another, thus permitting the device to be employed on any number of containers. With the device applied to the neck of the container in the heretofore described manner and with the cap in a closed position, it is impossible to remove the contents of the container without the employment of the key.

20 While I have shown and described the preferred embodiment of my invention, it will be understood that minor changes in construction, combination and arrangement of parts may be made without departing from the spirit and scope of my invention, as claimed.

25 Having thus described my invention, what I claim is:

1. A lock cap comprising a plate having slots, means for securing the plate to the neck of a container, a closure for the plate, hook shaped elements on the closure and extending through the slots, and a key actuated means for securing the cap to the plate.

30 2. A lock cap comprising a plate having slots, means for securing the plate to the neck of a container, a closure for the plate, hook shaped elements on the closure and extending through the slots, an inner closure member disposed in the neck of the container and having a marginal flange overlying the plate and a key actuated means between the first named closure and the inner closure for adjusting them relative to each other.

35 3. A lock cap comprising a plate having slots, means for detachably securing the plate to the neck of a container, a closure for the plate and concealing said means, hook shaped elements on the closure and extending through the slots, a cup shaped member disposed in the neck of the container, a marginal flange on said cup shaped member and overlying the plate, and a key actuated means between the closure and the cup-shaped member for securing the closure to the plate.

40 4. A lock cap comprising a plate having slots, a marginal flange for said plate, means for securing the plate to the neck of a container, an arcuate shaped member disposed in the neck, a marginal flange on the cup shaped element and overlying the plate, a closure received within the first named marginal flange, hook shaped elements on the closure and received within the slots, a stem journalled to the cup shaped elements, a

post on the closure and threaded to the stem, and a reduced shank on the stem to be engaged by a key.

45 5. A lock cap comprising a plate having slots, and disposed about the neck of a container with a portion of the material of the container disposed thereover, a sleeve in the neck, a marginal flange on the sleeve and overlying the material of the neck disposed over the plate, fasteners extending through the flanged material of the neck and plate, a closure over the plate, hook shaped elements on the closure and extending through the slots, and a key actuated means for securing the closure to the plate.

50 In testimony whereof I affix my signature.
FREDERICK GREENE.
